(57) **CLAIM**

The ornamental design for a dining chair component, as
shown and described.

DESCRIPTION

FIG. 1 is a front elevational view of my new design.

FIG. 2 is a rear elevational view thereof.

FIG. 3 is a right side elevational view thereof, the left side
elevational view being a mirror image thereof.

FIG. 4 is a top plan view thereof; and,

FIG. 5 is a bottom plan view thereof.

The broken lines in FIGS. 1, 2 and 3 are for illustrative
purposes only and form no part of the claimed dining chair
component.
